(57) **CLAIM**

The ornamental design for an electric pruning shears as shown and described.

DESCRIPTION

FIG. 1 is a front, left, and top perspective view of an electric pruning shears in accordance with our new design;

FIG. 2 is a rear, right, and bottom perspective view of the electric pruning shears in accordance with our new design;

FIG. 3 is a front elevational view of the electric pruning shears in accordance with our new design;

FIG. 4 is a rear elevational view of the electric pruning shears in accordance with our new design;

FIG. 5 is a top plan view of the electric pruning shears in accordance with our new design;

FIG. 6 is a bottom plan view of the electric pruning shears in accordance with our new design;

FIG. 7 is a right side elevational view of the electric pruning shears in accordance with our new design; and,

FIG. 8 is a left side elevational view of the electric pruning shears in accordance with our new design.

The broken lines in the drawings illustrate portions of the electric pruning shears which form no part of the claimed design.

1 Claim, 8 Drawing Sheets
